UNITED STATES PATENT OFFICE.

HARRY G. MOULDER, OF KANSAS CITY, MISSOURI.

AMUSEMENT DEVICE.

Application filed November 13, 1922. Serial No. 600,621.

To all whom it may concern:

Be it known that I, HARRY G. MOULDER, a citizen of the United States, residing at Kansas City, in the county of Jackson and State of Missouri, have invented a new and useful Amusement Device, of which the following is a specification.

My invention relates to amusement devices, and the object of the invention is to provide a manually operable machine having facilities for spinning a circular disk bearing thereon names of articles or things arranged in a circular series and normally concealed by a rotatable disk shutter having an opening therein adapted for observation of the names, one at a time, and for bringing the spinning disk to stop in position to disclose the names through the shutter.

A further object of the invention is to provide a portable device of this character which may be displayed at shop counters and soda fountains to entertain and amuse customers and thereby accelerate trade.

I attain these objects and other advantages by means of the mechanism illustrated in the accompanying drawing in which Figure 1, is a sectional view of a device embodying my invention: Figure 2, is a top plan view of the spinning disk, a part of my invention: Figure 3, is a vertical section of the rotatable shutter, a part of my invention: Figure 4, is a plan view of the clutch lever for driving the spinning disk wheel: Figure 5, is a top plan view of the spider bearing member: Figure 6, is a top plan view of the base: and showing the bearing plate therein: Figure 7, is a top plan view of a machine for the accommodation of several customers at the same time: Figure 8, is a vertical section of the shutter device: Figure 9, is a side elevation of the shutter device: Figure 10, is a top plan view of the automatic lever for imparting motion to the spinning disk and, Figure 11, is a top plan view of the star detent for detaining the spinning disk in position to disclose the names it bears through the shutter.

Similar numerals of reference refer to corresponding parts throughout the several views.

Referring to the drawings—the numeral 1, designates the housing which has an annular shoulder 2, at the upper end thereof, and on the shoulder is lodged a circular plate 3,

having a plurality of circular series of holes 55 therein, shown at 4, and at the center of the series of holes is a bearing hole 5, and in a circle about the hole 5, are a circular series of indentations 6. An annular bezel 7, is screwed on the upper end of the housing and 60 the flange portion thereof is brought to bear on the edge of the plate 3, to hold the same in place. In the lower portion of the housing is a bearing plate 8, which is held in place by screws 9, which are extended 65 through the housing and penetrate the edge of the plate. In the lower end of the housing is a circular hollow housing base 10, which is arranged to abut the lower side of the bearing plate. Through the central 70 part of the bearing plate is a large hole 11, of suitable size to permit the passage therethrough of a spur gear 12. Adjacent the hole 11, in the bearing plate are a circular series of pivot holes 13. On the lower side 75 of the plate 3, is mounted a spider 14, having radial arms 15, in the ends of which are pivot holes 16, which are adapted for registering with the pivot holes 13, and together receive the pivot 17, on the upper end of 80 which is mounted a gear wheel 18, and on the lower end thereof is mounted a bell shaped member 19. A revolute shaft 20, is aligned with the shaft 17, and its lower pivot end 21, is mounted in 85 the pivot hole 13; the upper pivot end thereof is mounted in the axial center of the lower end of the shaft 17. On the shaft 20, and projecting upward into the bell 19, is mounted a clutch member 22, having on its 90 upper end spaced apart lugs 23, between which lugs is pivotally mounted a horizontally disposed lever 24, the outer end of which is drawn to a point. The lever 24, is pivoted on the member 22, in such a manner that the outer end of the lever shall normally be free of the inner side of the bell, and the inner end portion thereof shall bear on the side of the member 22. On the lower end of the member 22, is a spool 25, 100 having flanges 26, between which flanges is imposed a yoke 27, on the end of a pivoted lever 28, the outer end portion of which projects outwardly of the housing, through a slot 29, therein, a suitable distance to facilitate the manipulation of the lever by hand. The lever is pivoted on a bracket 30. On the side of the lever is a semispherical de-

tent 31, which is adapted for seating in the indentations 32, in the wall of the slot 29, to hold the lever in place. The pivot on the member 22 is arranged to permit vertical movement of the member, by manipulating the lever 28 a suitable distance to allow the outer end of the lever 24 to frictionally engage and disengage the inner side of the bell shaped member 19. On the inner side of the housing are mounted inwardly projecting brackets 33, in the inner ends of which are pivot holes 34, in which are mounted the lower pivot ends 35, of vertical shafts 36, and having pinions 37, thereon and a star detent wheel 38, which is engaged by a pivotally mounted pawl 39, provided with a retractile spring 40, to hold the pawl in engagement with the detent wheel 38. On the shaft is also mounted a disk wheel 41, on the upper surface of which is a circular series of names of articles, as shown at 42, which are arranged thereon to be normally visible through the holes 4 in the plate 3, the upper side of the disk being disposed closely adjacent the lower side of the plate 3. At the axial center of the disk wheel 41, is a depression 43, adapted for receiving therein a pivot bearing member 44, which is mounted on the lower side of the plate 3, and vertically aligned with the shaft 36, are mounted spindles 45, on which spindles are rotatably mounted shutters members 46, comprising a disk portion 47, having cut away portions 48, dimensioned and arranged to permit observation of the names on the disk wheel 41, one at a time, the upper side of which disk portion is a vertically extending mass having a bore 49, adapted for loosely receiving therein the spindle 45, and a bore 50, having yieldingly mounted therein a detent 51, adapted for engaging the indentations 6, to detain the shutter so that the opening therein shall be positioned directly over the hole in the plate to permit observation of the marks on the disk wheel, the detent wheel 38 and the indentations are arranged upon parallel radial lines corresponding with the radius of the openings in the plate and the radius of the names inscribed on the disk wheel. The spur gear is mounted on a vertically extending shaft 53, which is revolubly mounted in the lower end of the spider 14, and in a bearing 54, associated with the base 10. On the lower end of the shaft 53, is a beveled gear wheel 55, which is driven by a gear wheel 56, mounted on a crank shaft 57. On the shutter 46, is a wing 58, which is usable as a handle to manipulate the shutter, and on the outer end of the clutch lever 28, is a thumb piece 59. On the upper end of the shaft 36, is a pivot 60. The spider 14, is provided with a vertical hole 61, having internal screw threads to receive a screw 62, which is extended through the plate 3, to hold the latter in place, and

screws 63, are extended through the plate and penetrate the upper end of the spider to hold the spider in place.

To operate the device the crank shaft 57, is turned to the right when the gear 56, will turn the gear 55, to the right, and likewise turn the spur gear 12, the latter gear turning the pinion 64, on the member 22, to the left, thereby revolving the member mentioned to the left, the lever 24, being thereby moved to turn by centrifugal force to approach the inside wall of the bell shaped member, in the well understood manner. If it is desired to impart motion to the spinning disk wheel 41, the lever 28, is pressed down until the detent 31, thereon is entered in the lower of the indentations 32, the yoke 27, on the inner end of the lever 28, thus elevates or raises the member 22, to a height sufficient to bring the outer end of the lever 24, to frictionally bear on the inner wall of the bell shaped member 22, the actuation of the bell shaped member by the lever being shown by the dotted lines 65, in Figure 1. The bell and the pinion 18, associated therewith are turned to the right, the pinion mentioned turning the pinion 37 to the left, thus the disk wheel 41, is turned and kept turning until the lever 28, is released to allow the member 22, to drop to normal position and the detent 31, in the lever enters the upper of the indentations 32, whereupon, the disk wheel and associated parts will keep turning until brought to a stop by the friction of the parts, when the detent pawl 39, will come to rest in the depression of the detent wheel and thereby bring the disk wheel in position to present the circular series of names thereon to the series of holes in the plate 3, so that one of the names may be seen through the opening in the shutter, the latter being held in position to expose one of the names by the detent 51, entering one of the depressions 6, in the plate. The detent wheel 38, is provided with a suitable pitch to allow the detent pawl 28, to come to rest to properly position the disk wheel. If the momentum of the disk wheel should carry the detent pawl beyond the center or place of rest as the disk wheel is about to stop, the tension of the retractile spring will pull it back to its proper resting place.

If, for instance, a customer approaches a soda fountain where one of the devices is displayed, and he is undecided as to what he shall order he may operate the device to select the particular kind of refreshment he shall take. He rotates the shutter 46, until he makes his selection, which name selected he leaves exposed to view through the opening in the shutter. The crank shaft is then turned and the clutch lever depressed to elevate or raise the clutch member 22, to a point where the end of the lever 24, will

frictionally engage the inner side of the bell shaped member, thereby, imparting motion to the latter and to the disk wheel 41. The clutch member being returned to normal position after a substantial impulse is given to the bell shaped member and associated parts, they continue to turn until they become inert, when one of the names of the circular series of names on the upper side of the disk wheel 41, will be visible in the opening in the shutter 46, which name is the name of the refreshment he shall order. Although one unit is shown, it is obvious that a number of units may be assembled in a single housing and all of them driven by the centrally disposed spur gear 12, a top plan view of such an assembly is shown in Figure 7, thus affording opportunity for a number of persons to participate in the amusement at the same time. The disk wheel 41, may bear thereon trade names of any merchandise, such as candy, gum, cigars, cigarettes, and the like, and provide amusement and entertainment, besides, accelerating trade in the store or shop, where the device may be placed on the counter or other convenient support.

Having described my invention what I claim is—

- 30 1. An amusement device, comprising a housing member, a plate mounted on the upper end of said housing member and having a circular series of circular openings therein, a pivotally mounted disk wheel bearing upon its upper face a circular series of words or marks, a detent wheel associated with said disk wheel, a yielding pivotally mounted lever having a detent in engagement with said detent wheel to normally hold said disk wheel in position to present the circular series of words or marks thereon to the circular series of openings in said plate, a pinion associated with said disk wheel, a revolubly mounted shaft provided 35 with a gear wheel enmeshed with said pinion and with a bell shaped member, a revoluble slidably mounted clutch member vertically aligned with said shaft, said clutch member comprising a body portion provided with a horizontally disposed pivoted lever adapted to be turned by centrifugal force to impinge upon the inner side of the bell shaped member, a spool associated with said clutch member, a pivotally mounted lever having a yoke 40 engaging said spool to raise and lower said clutch member, a pinion associated with said clutch member, a revolubly mounted spur gear wheel enmeshed with said last mentioned pinion, a disk shutter rotatably mounted on said plate having an opening therein adapted for permitting a view of one of the circular series of words or marks on said disk wheel through the openings in the plate, a yielding pivotally mounted detent mounted in said shutter and arranged therein to traverse the circular series of indentations or depressions in said plate to hold the shutter in place, and power receiving and power imparting devices for driving said spur gear wheel and thereby impart motion to said clutch member.

clutch member, a revolubly mounted spur gear wheel enmeshed with said last mentioned pinion, and power receiving and power imparting devices for driving said spur gear wheel and thereby impart motion to said clutch member.

2. An amusement device, comprising a housing member, a plate mounted on the upper end of said housing member and having a circular series of openings therein and a circular series of indentations or depressions within the circle of openings, a pivotally mounted disk wheel bearing upon its upper face a circular series of words or marks, a detent wheel associated with said disk wheel, a yielding pivotally mounted lever having a detent in engagement with said detent wheel to normally hold said disk wheel in position to present the circular series of words or marks to the circular series of openings in said plate, a pinion associated with said disk wheel, a revolubly mounted shaft provided with a gear wheel enmeshed with said pinion and with a bell shaped member, a revoluble slidably mounted clutch member vertically aligned with said shaft, said clutch member comprising a body portion provided with a horizontally disposed pivoted lever adapted to be turned by centrifugal force to impinge upon the inner side of the bell shaped member, a spool associated with said clutch member, a revolubly mounted spur gear wheel enmeshed with said last mentioned pinion, a disk shutter rotatably mounted on said plate having an opening therein adapted for permitting a view of one of the circular series of words or marks on said disk wheel through the openings in the plate, a yielding pivotally mounted detent mounted in said shutter and arranged therein to traverse the circular series of indentations or depressions in said plate to hold the shutter in place, and power receiving and power imparting devices for driving said spur gear wheel and thereby impart motion to said clutch member.

HARRY G. MOULDER.
